UNITED STATES PATENT OFFICE.

MAX R. HYMAN, OF INDIANAPOLIS, INDIANA.

EXPANSIBLE SEPTIC TANK.

1,389,553.

Specification of Letters Patent. Patented Aug. 30, 1921.

Application filed March 14, 1921. Serial No. 451,995.

To all whom it may concern:

Be it known that I, MAX R. HYMAN, a citizen of the United States, residing at Indianapolis, in the county of Marion and State of Indiana, have invented a new and useful Expansible Septic Tank, of which the following is a specification.

The object of my invention is to produce a series of concrete slabs of such character that they may be readily handled manually and assembled by comparatively unskilled workmen into a septic tank of any desired capacity and shape in accordance with the needs and available area of any particular 15 location.

The accompanying drawings illustrate my invention: Figure 1 is a fragmentary perspective view of a three-compartment receiving chamber of a septic tank formed by my improved sections or slabs; and Fig. 2 is a longitudinal section, on a smaller scale.

In the drawings 10 indicates a slab, preferably of concrete suitably reinforced, used as bottoms, tops and imperforate sides, to 25 form a compartment. Slab 10 is preferably formed, as indicated, with a continuous rabbet 11 around its sides so proportioned that six of said slabs may be brought together in box form and sealed by a suitable 30 cement at the joints.

I also provide special end slabs 12 perforated at 13 to receive a standard elbow 14 to serve as inlet and outlet for the completed tank.

35 Perforated partition slabs 15 are provided to separate the system into the successive chambers which are necessary to obtain the clarifying and sewage disposal action which is well known. In order to obtain desired 40 capacity in the several chambers of the system I provide the peculiar two-part partition slab composed of the two identical parts or slab pieces 15-15 which are cut away at one corner. The precise manner of 45 form of the cut away portion being immaterial so long as there is provided a sufficient footing width at the narrow part, as clearly indicated in Fig. 1, the arrangement

being such that two slab sections 15, when put together in any arrangement, will provide a full and adequate support for the top slabs 10. The construction of these central slab members 15 is such that by varying the arrangement, as indicated in Fig. 1, a serpentine flow of liquids may be obtained 50 from one part of a chamber to another. The cut-away portion or corner of the slab section 15 has a height less than the normal working depth of the liquid in the tanks so that the film 16 of microorganism will be 55 unbroken by the flow of liquid from one part of the chamber to another.

It will be noted that the various slabs 10, 12, and 15-15 are interchangeable so that all sorts of relative arrangements of successive small chambers, communicating with each other along the bottom, through the opening formed by the cut away portions of slabs 15, or communicating through the perforations 13, may be provided depending 60 upon the shape and area of the ground which may be available for placing of the system. The slabs are made of such size and weight that they may be readily handled by two workmen who without any great skill, 65 may readily produce from the standard slab elements, any desired septic 10.

I claim as my invention:

1. A septic tank formed from an interchangeable series of slab elements comprising separate top, bottom and side elements, each of said elements having a rabbet formed along each edge of one face and of substantially one half the thickness of the slab, and a two part partition, one corner of each 85 part being absent, substantially as shown and described.

2. A two part partition for septic tanks co-operatively formed by two slab elements, each of which has one corner absent substantially as shown and described.

In witness whereof, I have hereunto set my hand at Indianapolis, Indiana, this 5th day of March, A. D. one thousand nine hundred and twenty one.

MAX R. HYMAN.
